UNITED STATES PATENT OFFICE.

RAY FREEMAN, OF PERRINE, FLORIDA.

CHAIR FOR RAIL JOINTS.

Application filed October 26, 1920. Serial No. 419,691.

To all whom it may concern:

Be it known that I, RAY FREEMAN, a citizen of the United States, and a resident of Perrine, in the county of Dade and State 5 of Florida, have invented certain new and useful Improvements in Chairs for Rail Joints, of which the following is a specification.

My invention relates to improvements in 10 chairs for rail joints, and it consists substantially in the construction and manner of use herein described and claimed.

One of the foremost objects of the invention is to provide a chair designed to absolutely prevent sagging and side play.

Other objects and advantages will appear in the following specification, reference being had to the accompanying drawing, in which:

20 Figure 1 is a plan view of the improved chair, only so much of a rail being shown as is necessary to illustrate the application, and

Figure 2 is a cross section on the line 2—2 of Figure 1.

25 Attention is first directed to Figure 2. The chair which constitutes the invention, comprises the sole plate 1, which is formed at 2 to embrace the outer flange 3 of the rail base, thereafter extending vertically into a 30 part hereinafter properly termed the fish plate 4. The fish plate includes an upward extension 5, which preferably rises slightly above the head of the rail so that it may be engaged by the sloping face of the wheel. 35 The ends of the extension 5 are inclined at 5^a so that there will be no jar when the wheels strike the extension in going over the joint.

This extension 5 is of no little importance 40 because it serves to support the weight of the wheels and the train above in passing the joint. The usual pounding, jarring and vibration occasioned by the wheels 7 moving over the space between two abutting rails 6, is thus entirely eliminated by the provision 45 of the extension 5. A shoulder 8 fits snugly against the rail head on the outside, as is somewhat common in practice.

There is a recess 9 in the bend 2 in which 50 the outer flange of the rail base fits in a rather peculiar manner. Instead of the walls of the recess contacting similar parts of the flanges 3 throughout, only the innermost part of the top of the recess is intended 55 to engage the flange. The recess then be-

comes slightly larger so as to leave the tapering space illustrated.

Observation has shown that a jar can occur even when the rail ends 6 are tight together, thus indicating that the jar is not produced by the wheels passing over an open space between adjacent rails. The jar is really caused by the sagging of the rails at the joint, thus forming a valley into which the wheels ride, striking the rail at 65 the opposite side from the point of entrance and thus causing what is commonly known as a jar.

It is the purpose of this invention to prevent sagging, thus eliminating the jar, and 70 also sidewise play of the rails. When the lateral thrust of the car wheels 7 is exerted against the rails at the joint, a tendency to tighten them at the points indicated 10, becomes evident. The space afforded by the 75 peculiar shape of the recess 9 provides ample room for the tightening of the flange at the bottom, and the chair therefore becomes self-adjusting by virtue of the slight flexibility afforded as just described. 80

In making these plates, they will be rolled a trifle close in the space between the point 10 and the bottom of the sole plate 1, with sufficient space at 9 so that there will be no interference, always permitting a perfect fit 85 at 10. By a tool, designed especially for the purpose of fitting these plates, the sole plate will be supported along the inner edge and pressure applied to the fish plate and chair 90 between and on either side of the rail securing bolts. This will insure a close fit at the points 10, and across the top of the sole plate 1.

By having a proper thickness of plate 95 over the space 9, the strain will be transmitted through the bend 2 to the plate 1, which will then be in tension and offer a sufficiently strong mass from the top of the extension 5 to the bottom of the plate 1, to resist sagging. 100

Spikes 11 secure the chair in place. The bend 2 is vertically recessed at 12 to provide a place for the outermost spike to fit in, but the innermost spike is driven through a hole 13 in the inner part of the sole plate 1, which 105 extends well beyond the inner flange of the base. A fish plate 14, which may be of any ordinary construction, includes a recess 15 on the inner edge, through which the innermost spike 11 also passes. 110

2
There is another feature of no little importance. As in many rail joint-making constructions, a lock washer 16 is used in connection with the nut 17 of the securing bolt 18. But instead of letting the lock washer 16 rest on the outer surface of the chair 4, a recess 19 is provided for its reception. The now common danger of the washer jarring out and leaving the bolt loose in case the washer should break, is entirely obviated by housing the washer in the recess. Even should it break, the bolt cannot come loose because the parts of the washer are prevented from falling away.

15 While the construction and arrangement of the improved chair as herein described and claimed, is that of a generally preferred form, obviously modifications and changes may be made without departing from the 20 spirit of the invention or the scope of the claims.

I claim:—

1. The combination in a rail joint, of a sole plate sufficiently wide to extend well 25 beyond the inner flange of a rail base, perforated to receive spikes; an inner fish plate bearing against a rail head and inner flange, extending from the flange and provided with notches registering with said spike perforations; a bent portion extending from the

sole plate and embracing the outer flange of a rail base, including a recess contacting said base flange at the innermost point to provide adjusting space; and a fish plate extending from said bent portion, including a shoulder contacting beneath a rail head, with an upward extension coming flush with the top of the rail head for the support of car wheels across the rail joint, and a recess in the side of the fish plate for the housing 40 of a lock washer of a bolt which secures the parts together. 35

2. The combination in a rail joint, of a sole plate sufficiently wide to extend well beyond the inner flange of a rail base, perforated to receive spikes; an inner fish plate bearing against a rail head and inner flange, extending from the flange and provided with notches registering with said spike perforations; a bent portion extending from the 50 sole plate and embracing the outer flange of a rail base, including a recess said bent portion contacting said base flange at the innermost point only to provide adjusting space; and a fish plate extending from said bent portion, including a shoulder contacting beneath a rail head, said fish plate having a recess in one side for housing a lock washer of a bolt which secures the parts together. 45 55

RAY FREEMAN.
